UNITED STATES PATENT OFFICE.

BERTIE PATERSON, OF LONDON, ENGLAND.

COIN-FREED GAS-METER.

SPECIFICATION forming part of Letters Patent No. 656,042, dated August 14, 1900.

Application filed February 15, 1900. Serial No. 5,348. (No model.)

To all whom it may concern:

Be it known that I, BERTIE PATERSON, a subject of the Queen of Great Britain, residing at 31 Clerkenwell Green, Clerkenwell, London, England, have invented new and useful Improvements in or Connected with Coin-Freed or Prepayment Gas-Meters, of which the following is a specification.

This invention relates to improvements in or connected with coin-freed or prepayment gas-meters of the kind wherein by the aid of a coin a normally-locked handle is freed to enable the purchaser to turn the same through a predetermined distance, the rotation of the said handle revolving a screw, thus setting forward a toothed wheel upon the same through a predetermined distance and opening the gas outlet or inlet valve, so as to allow gas to pass through the meter, the passage of the gas effecting the return of the said toothed wheel by means of an elongated pinion placed parallel with the screw.

The invention has for its object to improve this class of prepayment gas-meter.

In the accompanying drawings, Figure 1 is a sectional elevation of a portion of a coin-freed or prepayment gas-meter having my improvements applied thereto. Fig. 2 is a sectional plan thereof. Fig. 3 is a section on the line 3 3, Fig. 2; and Fig. 4 is a section on the line 4 4, Fig. 3. Fig. 5 is a view similar to Fig. 3, but showing the parts in different relative positions.

a is the meter-casing, b the screw, c the toothed wheel mounted upon the same, and d the elongated pinion which is placed parallel with the screw b, all of these parts being arranged in the attic of the meter.

e is a casing which is externally fitted to the meter-casing a and carries the rest of the prepayment mechanism. This mechanism comprises the coin-carrier for receiving the coin introduced into the mechanism, the said carrier consisting of the two end plates f f, which are formed with slots f' f' to receive the coin and are mounted upon the spindle f'', which is supported in bearings in the frame-plates g g and has an external handle or crank f'', whereby it can be turned in the usual way. The spindle f'' is provided with a crown-wheel h, which gears with an elongated pinion h' on the spindle h'', mounted in the casing e, the

said pinion h' being adapted to effect the rotation of the feed-screw b either directly or indirectly. In the drawings it actuates the 55 said feed-screw b through the medium of the toothed wheel h'', which is mounted upon one end of the said feed-screw b externally to the meter-casing and inside the casing e. The crown-wheel h also serves as a price-changing 60 wheel to enable the apparatus to be adapted to deliver different quantities of gas for each coin inserted, according to the price of gas in a particular locality. The coin-carrier is normally held against rotation by means of a pawl i, pivoted at i' to the casing e and having two pins i'' i'', which engage peripheral notches or slots i''' i''' in the end plates f f of the carrier, and by means of a second or gravity pawl j, pivoted at j' to the casing e. This pawl j normally engages a depression or tooth k upon a cam-disk k', mounted upon the carrier-spindle f'', and is also extended upward to form a shutter j'' for closing the coin-slot l in the casing e, as hereinafter described, when a coin 75 is in the carrier. It will also be seen that the pawl j forms a chute or guide for the coins inserted in the mechanism. With this arrangement when a coin A is inserted in the apparatus it drops into the slots f' f' in the end 80 plates f f, and in its passage into the said slots releases the gravity-pawl j from engagement with the cam-disk k', moving it into the position shown in broken lines in Fig. 3, in which position the shutter j'' is brought underneath 85 the coin-slot l, so as to close it. The cam-disk k' being thus released, the carrier f can be rotated by the handle f'', the peripheral notches i''' in the end plates f f permitting a slight amount of movement. This initial 90 movement of the carrier, however, causes the coin A to lift the pawl i from these peripheral notches i'', as shown in Fig. 5, thereby completely releasing the carrier and allowing it to be turned farther until the coin falls from 95 the carrier f and the latter resumes its normal position, when the gravity-pawl (which during the latter portion of the movement has ridden upon the periphery of the cam-disk k' and thereby kept the money-slot closed) again 100 drops into engagement with the tooth k and locks the carrier, upon which the shutter j'' is withdrawn and the money-slot l reopened to receive another coin, and so on. The ro-

tation of the spindle f^2 has turned the crown-wheel h , which through the medium of the toothed gear $h' h^3$ has set forward the toothed wheel c upon the screw b to an extent corresponding to one coin's equivalent of gas.

5 $i^4 i^4$ are peripheral slots formed in the end plates f , into which the pawl-pins i^2 drop as soon as the coin falls from the carrier, so as to prevent the latter from being turned back.

10 The toothed wheel c , which rides upon the feed-screw b in the attic of the meter, is of special construction—that is to say, it is formed upon one face with a number of projections or teeth c' , preferably somewhat radial, the grooves forming the teeth upon the wheel c extending onto the peripheries of the said projections. These teeth or projections c' have for their object to engage with a star-wheel m when the toothed wheel c has been

15 returned by the action of gas passing through the meter to the initial position, the engagement of the teeth c' at any point with the star-wheel m effecting the closing of the gas outlet or inlet valve. To this end the star-wheel m is mounted upon a spindle m' , which is supported at one end in a stuffing-box n on a closed chamber n' , containing a crank-arm o , keyed to the spindle and connected to the valve spindle or stem p and at the other end

20 in a recess b' in the feed-screw b . To enable the gas to be gradually and not suddenly cut off, so as to give notice to the consumer that a further purchase of gas must be made, I form the valve-stem p with a cone-shaped lower end p' , having a dish-shaped or recessed disk or valve proper, q . With this arrangement the gradual closing of the valve gradually decreases the area of the gas-outlet passage r until the dish-shaped disk q completely 25 closes the said passage.

To close the coin-slot when the number of coins for which the machine is adapted has been introduced into the apparatus, I provide a weighted crank-plate s , pivoted in the frame-45 plates $g g$ and having a pallet s' and rod s^2 , which extends into and is carried in the attic of the meter. The rod s^2 is pivoted to the plate s and has a projection s^3 , against which the toothed wheel c , riding on the screw b , impinges upon reaching the forward end of the said screw, so as to bring the pallet s' against the pawl j and move the shutter j^2 under the coin-slot t , which, however, reopens on the consumption of one coin's equivalent of gas.

55 t is a disk numbered from "0" to "11" for indicating the number of pence inserted in the mechanism, the said disk t being fixed upon the spindle t' , mounted in the bracket g' in the casing e and carrying a worm-wheel t^2 ,

60 which gears with a worm t^3 upon the carrier-spindle f^2 , the gearing being so arranged that the disk t moves forward one figure for each revolution of the handle f^3 . A second disk u is also provided, the said disk being numbered to indicate in shillings the amount of money inserted in the apparatus. This is indicated by a pointer u' , keyed upon a spindle

70 u^2 , mounted in the bracket g' and having a worm-wheel u^3 , which gears with a worm u^4 upon the spindle t' . A window v is provided behind the hinged front e' of the casing e to enable the indications upon the disks to be read off.

Having now particularly described and ascertained the nature of my said invention and 75 in what manner the same is to be performed, I declare that what I claim is—

1. In a coin-freed apparatus, the combination with the rotatable coin-carrier provided with coin-engaging portions, of a pawl normally engaging said carrier and having a part adjacent to the coin-engaging portions of the carrier adapted to be engaged by the coin as it enters the carrier, to disengage said pawl from the carrier, a second pawl normally engaging said carrier and having a part in the path of the coin as it is carried around in the carrier for disengaging said second pawl from the carrier, substantially as described. 80

2. In a coin-freed apparatus, the combination with the rotatable coin-carrier provided with coin-engaging portions, of a pawl normally engaging said carrier and holding it against forward movement, said pawl having a part adjacent to the coin-engaging portions 95 of the carrier adapted to be engaged by the entering coin to disengage the pawl from the carrier, a second pawl engaging elongated cut-away portions of the carrier to permit a limited forward movement of the carrier but preventing the rearward movement of the carrier, said pawl having a part in the path of the coins carried by the carrier to disengage the pawl from the carrier, substantially as described. 100

105 3. In a coin-freed apparatus, the combination with a casing provided with a coin-slot, a rotatable coin-carrier within the casing having coin-engaging portions, a pawl normally engaging the carrier to prevent its forward movement, provided with a shutter adjacent to said coin-slot, adapted to close the same when the pawl is disengaged from the carrier, said pawl having a part in the path of the entering coin for disengaging the coin from the carrier, a second pawl normally engaging the carrier and having a part in the path of a coin carried by said carrier for disengaging said second pawl when the carrier is rotated, substantially as described. 110

115 4. In a coin-freed apparatus, a coin-carrier comprising two slotted end plates mounted upon a rotatable spindle, a cam-disk keyed upon the said spindle, a gravity-pawl normally locking the cam-disk and adapted to be 120 unlocked by the weight of the coin and a pawl normally locking the coin-carrier and adapted to be unlocked by the coin when the carrier is rotated, substantially as described.

125 5. In a coin-freed or prepayment gas-meter, 130 the combination with a rotatable coin-carrier, a pawl holding said carrier from forward movement and having a part in the path of an entering coin, a second pawl engaging the

carrier and having a part in the path of a coin carried thereby, a screw-shaft operatively connected with said rotatable carrier, a pinion having a threaded aperture engaging said 5 shaft, an elongated pinion gearing with said first-mentioned pinion and operatively connected with the registering apparatus of the meter, a cut-off valve and an operating device for the cut-off valve in the path of said 10 threaded pinion, substantially as described.

6. In a coin-free or prepayment gas-meter, the combination with a casing provided with a coin-slot, a rotatable coin-carrier adapted to receive coins from said slot, a locking-pawl 15 normally engaging said carrier to prevent its forward movement and having a part in the path of the entering coin to disengage the pawl from the carrier, said pawl having operatively connected therewith a shutter for closing the 20 coin-slot when said pawl is disengaged from

the carrier, a second pawl engaging said carrier and having a part in the path of a coin carried by said carrier, a screw-shaft operatively connected with said carrier, a pinion having a threaded aperture engaging said 25 screw-shaft, an elongated pinion meshing with said threaded pinion and operatively connected with the registering apparatus of the meter, a cut-off valve having an operating device provided with a part in the path of said 30 threaded pinion when moving in one direction along its screw-shaft, a device operatively connected with said shutter and located in the path of said threaded pinion when moving in the opposite direction along its screw- 35 shaft, substantially as described.
